(57) **CLAIM**

The ornamental design for a motor vehicle, toy and/or replica, as shown and described.

DESCRIPTION

FIG. 1 is a front perspective view of a motor vehicle, toy and/or replica;

FIG. 2 is a rear perspective view thereof;

FIG. 3 is a right side elevation view thereof, the left side being substantially a mirror image;

FIG. 4 is a front elevation view thereof;

FIG. 5 is a rear elevation view thereof; and,

FIG. 6 is a top plan view thereof.

The broken line showing of the motor vehicle, toy and/or replica is for the purpose of illustrating portions of the motor vehicle, toy and/or replica and forms no part of the claimed design.
